Primary Examiner — Lilyana Bekic*Assistant Examiner* — Courtney J Clark-Rasheed(74) *Attorney, Agent, or Firm* — Bartholomew Law PC;
Michael Bartholomew(57) **CLAIM**

The ornamental design for a bottle lid as shown and described.

DESCRIPTION

FIG. 1 is a front, left and top perspective view of a bottle lid, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of the bottle lid shown in a configuration of use; and,

FIG. 10 is a rear, right and top perspective view of the bottle lid shown in another configuration of use.

The dashed broken lines depict portions of the bottle lid that form no part of the claimed design.

1 Claim, 10 Drawing Sheets(56)
